CLOTH ROLL HOLDER

Filed Oct. 12, 1946

UNITED STATES PATENT OFFICE

2,554,812

CLOTH ROLL HOLDER

Jacob Buckman, New York, N. Y.

Application October 12, 1946, Serial No. 703,018

2 Claims. (Cl. 242—61)

1

This invention relates to holders for rolls of cloth or the like and of the general type of apparatus shown and claimed in my prior Patent 2,333,358, issued Nov. 2, 1943. In this apparatus there is employed a frame structure having a pair of vertical sockets, one of which may receive and permit rotation of the supporting pin of a vertically disposed roll-impaling and carrying member, or both sockets may receive supports for a horizontal roll.

The main objects of my invention are to simplify and reduce the cost of the apparatus, increase the rigidity, and better insure the firm securing of the apparatus on a table or other supporting structure.

As one important feature, I make the frame part substantially triangular in shape and adapted to rest on a table or bench with one edge provided with means for clamping it along the edge of a table. A socket is disposed at the apex so that a vertical roll may be supported at a substantial distance inwardly from the table edge.

As another feature, I make said frame substantially in the shape of a right angled triangle with a second edge substantially at right angles to the clamping edge and with sockets at opposite ends thereof so that a horizontal roll may be supported within its axis at right angles to the general direction of the edge of the table.

I provide a vertical roll-impaling member in the form of a blade extending upwardly from a base plate rotatably supported in the first mentioned socket, and, as one feature of my invention, I provide the blade with ridges on opposite faces and tapered along the length so that they may be forced into the core of the roll of cloth and more effectively secure it against movement in respect to said blade.

As a further feature, I provide a ball support at the lower end of the socket which receives the pin of the roll carrying blade so as to permit free rotation of the blade with the minimum friction and I provide means for guiding the pin into the socket and onto the ball.

Various other features will be hereinafter pointed out or will be apparent from a consideration of the drawings and the following description.

In the accompanying drawings,

Figure 1 is a top plan view of the apparatus clamped to one edge of a table;

Figure 2 is a side elevation of the parts shown in Fig. 1, a part being shown in section.

Figure 3 is a section on the line 3—3 of Fig. 2, and

2

Figure 4 is a side elevation of the frame member used to support a horizontal roll.

In the specific form illustrated, the frame member includes three sections or side members 10, 11 and 12 cast integral and united at their ends to form a right triangle. The section or side member 12 is designed and adapted to extend along, and parallel to, one edge of a table top or bench A and is provided with a pair of flanges 13, extending downwardly and then laterally beneath the table top A and provided with clamping screws 14 are rigidly securing the frame to the table top and parallel to the general length of the table.

15 The section member 10 of the frame extends at right angles to the section 12 and the section 11 extends at an acute angle to both the sections 10 and 12 so that the sections 10 and 11 converge at the point where they are formed integral with a vertical post 15, provided with a vertical socket 16. The post and the side members 10 and 11 may be reinforced and strengthened by flanges 17 and 18 on the upper sides of the sections and integral with them and with the post. At the 20 point of intersection of the side members 10 and 12, there is formed a second post 19 which may also be reinforced by the flange 18.

For supporting a vertical roll of cloth or of other material to be unwound, there is provided 25 a turntable 21 which may be formed integral with, or may be rigidly secured to, a blade 22 adapted to be forced endwise into the core of the roll. This blade has flanges or ridges 23 along opposite faces and substantially midway between opposite edges. These flanges are 30 tapered from the turntable to the upper end which end may be at, or somewhat below, the rounded upper end of the blade. The turntable is provided with a spindle 24 co-axial therewith and 35 on the under side and adapted to extend into the socket 16 of the post 15 and rest upon a ball 25 at the lower end of the socket. As the frame is preferably formed of cast metal, the socket is preferably provided with a liner 26 which may 40 be machined to have a close running fit with the spindle 24.

The upper end of the post 15 is provided 45 with a radially extending groove 27 of a curvature approximating that of the surface of the spindle 24. Thus, after the blade 22 has been 50 forced endwise into the core of a roll, the roll, blade and turntable may be positioned with the spindle 24 horizontal and lying in and supported by the groove 27. The outer end of the roll may 55 be then lifted to bring the axis of the roll into a

vertical position, and during this movement the weight of one end of the roll is supported by the spindle. As the spindle rests in the groove, lateral movement of the end of the roll is prevented. When the roll axis reaches a vertical position, the spindle will drop into the socket and be in the position shown in Figures 1 and 2. The cloth may then be pulled along the table for cutting, and during such unrolling the roll itself is supported in a vertical position and lateral movement is prevented by the triangular base which is clamped along the edge of the table.

As disclosed in Figure 13 of my prior Patent 2,333,358 hereinbefore referred to, it is often desirable to support a roll of cloth or other material with its axis horizontal instead of vertical during the unwinding. My present improved construction is equally adapted for supporting a roll with its axis vertical or horizontal. If a roll is to be mounted with its axis horizontal, the turntable 21 and blade 22 are removed from the socket in the post 15 and a pair of posts 30 and 31 are inserted in the sockets of the posts 15 and 19. These serve to support an extensible member 33 leading to another vertical post, not shown, and to support a roll B. The parts 30, 31 and 33 may be constructed substantially the same as the corresponding parts shown in Figure 13 of my prior patent and further description of these would seem to be unnecessary.

By having the two posts 15 and 19 in a line at right angles to the element 12 which extends along the edge of the table, it will be seen that the axis of the roll B will be definitely positioned at right angles to the general length of the table and the cloth being unrolled may be properly positioned on the table.

The frame member may be cast from any suitable metal having the required strength and

the parts 21 and 22 are preferably formed of aluminum or other light metal so as to reduce the weight but provide the necessary strength.

Having thus described my invention, what I claim as new and desire to secure by Letters Patent is:

1. A cloth roll holder, including a base frame adapted to be secured to a table and provided with a vertically disposed socket, a turntable, and a substantially flat roll-impaling member rotatably mounted in said socket, rigid with said turntable, and provided with ridges on opposite sides tapering upwardly from said table and adapted to be forced into the core of a roll of cloth.

2. A cloth roll holder having a frame adapted to be secured to a table and provided with a vertical post having a socket and a groove at the upper end thereof radial to said socket, and a roll-impaling member having a substantially flat blade, a turntable, and a spindle rigid therewith, said spindle being adapted to rest in a horizontal position in said groove and to be retained thereby against lateral movement during upward tilting movement to a vertical position and insertion in said socket.

JACOB BUCKMAN.
